CLAIM

The ornamental design for a pan as shown and described.

DESCRIPTION

FIG. 1 is a front, right perspective view of the pan showing my new design;

FIG. 2 is front view thereof;

FIG. 3 is rear view thereof;

FIG. 4 is right side thereof;

FIG. 5 is left side thereof;

FIG. 6 is top view thereof; and,

FIG. 7 is bottom view thereof.

The broken lines in the Figures are for the purpose of illustrating portions of the pan that form no part of the claimed design.

1 Claim, 5 Drawing Sheets
